UNITED STATES PATENT OFFICE.

FRANK HORNQUIST, OF MOUNT JEWETT, PENNSYLVANIA.

SAFETY SHOE FOR RAILWAY TRUCKS.

Continuation of application Serial No. 36,697, filed June 12, 1925. This application filed May 13, 1926.
Serial No. 103,920.

The invention relates to improvements in safety shoes for railway trucks to hold them against excessive lateral movement with regard to the rails, in case the wheels should 5 jump from said rails.

The object of the invention is to provide an exceptionally simple and inexpensive, yet an efficient and reliable device of the class set forth, which when in operation, 10 may readily slide along the rails and will have no injurious effects upon the latter or upon any parts of the truck.

With the foregoing in view, the invention resides in the novel subject matter herein- 15 after described and claimed, the description being supplemented by the accompanying drawing.

Fig. 1 is a side elevation of a truck equipped with the invention.

Fig. 2 is a top plan view partly in section.

Fig. 3 is a transverse sectional view on the irregular line 3—3 of Fig. 2.

Fig. 4 is a transverse section illustrating the manner in which the invention comes 25 into play when the truck wheels jump from the rails.

Fig. 5 is a detail section on line 5—5 of Fig. 3.

Before entering into the details of description, it may be stated that the present application is a continuation in part of my pending U. S. application, Serial No. 36,697, filed June 12, 1925.

In the accompanying drawing, a truck is 35 shown embodying the usual wheels W, side members S, and upper and lower bolsters U and L, respectively. Four of the attachments are shown, disposed at the ends of the bolsters, this number being preferable for a six wheel truck, whereas other numbers may be used if desired on trucks having more or less wheels.

Each of the attachments comprises a horizontally elongated shoe 6 whose length is disposed transversely of the truck when in use, said shoe 6 having beveled front and rear surfaces 7 which preferably although not necessarily meet at the lower side of said shoe, said beveled surfaces permitting free sliding of the shoe along a rail. The outer end of the shoe is widened by providing it with oppositely projecting integral lugs 9, and this widened end is provided with a downwardly projecting integral flange 10 for disposition at the outer side of a rail.

The inner end of the shoe 6 is also widened by providing it with oppositely projecting horizontal lugs 11, and this inner end is provided with a downwardly projecting roller 12 for disposition at the inner side of 60 the rail.

The lugs 9 are secured by bolts or the like 13 to the lower side of the side members S in the present disclosure, and by means of additional bolts 14 and a clamping member 15, the lugs 11 are secured to the lower bolster L. When the device is so installed, at proper places upon the truck, the shoe 6 is upwardly spaced from the rail, and the flange and roller 10 and 12 respectively, constituting auxiliary shoes, are disposed respectively at the outer and inner sides of the rail. Thus, in case the wheels W should jump from the rail, the shoe is in readiness to engage said rail and take the weight of 70 the car, and the auxiliary shoes will then, by engagement with the track, prevent the truck from moving excessively in either direction with respect to said track. Moreover, the shoes may readily slide along the 75 rails without injury to truck or track, until the car or train can be brought to a standstill.

The device is exceptionally simple and inexpensive, is efficient, reliable, and in every way desirable. Excellent results may be obtained from the details disclosed and they are therefore preferably followed, but within the scope of the invention as claimed, 80 variations may be made.

I claim:

1. In combination with a railway truck having a transverse bolster between two sets of wheels; a shoe rigidly mounted at the lower side of the truck at an end of said bolster, said shoe being elongated transversely of the truck, projecting both inwardly and outwardly from the plane of the wheels and having beveled front and rear surfaces, an auxiliary shoe projecting downwardly from the outer end of the first named shoe and disposed at the outer side of said wheel plane, and an additional auxiliary shoe projecting downwardly from the inner end of the first named shoe and disposed at the inner side of the wheel plane, the main and auxiliary shoes being normally supported above the lowermost plane of the truck wheels.

2. A safety attachment for disposition at

the end of a truck bolster, said attachment comprising a horizontally elongated member intended to have its length disposed transversely of the truck, said member having beveled front and rear surfaces and being provided with integral lugs at its inner and outer ends to receive fasteners for rigidly securing it to the truck, and auxiliary shoes projecting downwardly from the inner 10 and outer ends of said member.

3. An attachment for disposition at the end of a truck bolster, said attachment comprising a horizontally elongated member intended to have its length disposed transversely of the truck, said member having beveled front and rear sides and having oppositely projecting integral lugs at its inner 15 and outer ends to engage means for rigidly attaching it to the truck, an integral flange projecting downwardly from one end of said member and constituting an auxiliary shoe, 20 projecting downwardly from one end of said member and constituting an auxiliary shoe,

and a second auxiliary shoe projecting downwardly from the other end of said member.

4. An attachment for disposition at the 25 end of a truck bolster, said attachment comprising a horizontally elongated member intended to have its length disposed transversely of the truck, said member having beveled front and rear sides and having oppositely projecting integral lugs at its inner 30 and outer ends to engage means for rigidly attaching it to the truck, an integral flange projecting downwardly from one end of said member and constituting an auxiliary shoe, 35 and a roller projecting downwardly from the other end of said member and constituting a second auxiliary shoe.

In testimony whereof I have hereunto affixed my signature.

FRANK HORNQUIST.
